UNITED STATES PATENT OFFICE.

REX H. DYER, OF KANSAS CITY, MISSOURI.

DESIGN FOR A CHAIR.

Application filed June 14, 1928. Serial No. 27,121. Term of patent 3½ years.

To all whom it may concern:

Be it known that I, REX H. DYER, a citizen of the United States, residing at Kansas City, Jackson County, Missouri, have invented a new, original, and ornamental Design for a Chair, of which the following is a specification, reference being had to the accompanying drawing, forming part thereof, wherein—

Fig. 1 is a perspective view of a chair embodying my new design.

Fig. 2 is a side view of the same.

Fig. 3 is a plan view of the same.

I claim:

The ornamental design for a chair, as shown.

REX H. DYER.
